(57) **CLAIM**

I claim the ornamental design for a toothbrush with toothpaste-filled handle, as shown and described.

DESCRIPTION

FIG. 1 is a perspective view of a toothbrush with toothpaste-filled handle showing my new design;

FIG. 2 is an end elevational view thereof;

FIG. 3 is an elevational view of the opposite end thereof;

FIG. 4 is a side elevational view thereof, the elevational view of the opposite side being a mirror image thereof;

FIG. 5 is a bottom plan view thereof; and,

FIG. 6 is a top plan view thereof.
